UNITED STATES PATENT OFFICE.

SAMUEL BRADBURY, OF GRIGGSVILLE, ILLINOIS.

IMPROVEMENT IN MACHINES FOR TRIMMING HEDGES.

Specification forming part of Letters Patent No. 16,462, dated January 27, 1857.

To all whom it may concern:

Be it known that I, SAMUEL BRADBURY, of Griggsville, in the county of Pike and State of Illinois, have invented a new and Improved Mode of Trimming Hedges; and I do hereby declare that the following is a full, clear, and exact description of the construction and operation thereof, reference being had to the accompanying drawings, making a part of this specification, and to the letters of reference marked thereon.

The nature of my invention consists of a carriage-frame placed upon wheels to be drawn by two or more horses, with knives so arranged as to trim a hedge upon the side and top at the same time, the several parts of which machine are more particularly described as follows, to wit:

Figure 1 represents a top view of the machine. Fig. 2 represents a front elevation of the machine, reference being also had to the different parts of the invention represented in the drawings by letters. I construct a frame carriage resting on two wheels, B and C. On the left of the carriage is fixed a cogged driving-wheel, D, which drives a pinion, E, placed in front, which pinion is placed on the end of a shaft, F, that rests upon two arms, G, arranged for that purpose. On the other end of the shaft F is fixed a second driving-wheel, H, with bevel-cogs on the side and square cogs on the end. The side cogs meshes in a beveled pinion, I, which rests on the main axle J of the carriage, to which is attached a shaft, K, running across the axle J near its bearing. It is formed into a crank, E E, to which is attached an iron rod, L, which rod is also attached to a sliding knife or cutter, M, which extends along the side of the beam A, of any required length, which beam is hung upon a hinge, N, and is so constructed that the out end is easily raised or lowered and made firm at any given height, from one foot to five feet, or more, if required, from the ground, by a gage, Z, with pin-holes, while the knife or cutter M works freely in every position. There are two knives, M and O, which work in the manner of shears. One part of the knives is stationary, while the other part works freely. The moving knife M is supported by strong iron clasps P, under which it plies. The knife M also serves to hold the brush while being cut. The edge-cogs on the driving-wheel H also

drives another square pinion, Q, placed under the beveled wheel J, to which is attached a shaft, R, extending parallel with the main axle J to a post, S, which rests on the right end of the axle J. On the shaft R is a crank, T, to which is attached an iron arm, U, extending nearly to the top of the post S, which is also attached to another sliding knife or cutter, B B, which plies through iron fingers V, but nearly in a perpendicular position. This arrangement is intended to trim the side of the hedge, while the movable beam A and knife or cutter M will cut the top at any stage from its first start to a full grown hedge. The right-hand wheel, C, of the carriage is placed a little back of the right end of the main axle J, between two arms, W, arranged for that purpose. There is also a circling brace, X, which is made fast to the out end of the arms W and to the top end of the post S; also, another brace, Y, made fast near the bottom of the circling brace X, which supports the elevated beam A. I also place a tongue, A A, in front on the right of the second driving-wheel, H, a little past the center toward the left, which leaves room for the off horse between the tongue and the hedge.

C C represent a beam, and D D a shaft, which was intended as a mower or grass cutter, but is not considered as a part of this specification.

Operation: My machine is drawn by two horses, and is driven along the side of the hedge, while the knives ply freely, the up-and-down knives trimming the side of the hedge, while the knives on the elevated beam plies at the same time, cutting the top of the hedge, sloping up, then driving upon the other side of the hedge, trimming it in the same manner, which completes the trimming and leaves the top of the hedge roofing and a little the widest at the bottom.

What I claim as my invention, and desire to secure by Letters Patent, is—

The arrangement of the adjustable cutters M and vertical cutters B B, operated in the manner and for the purposes herein set forth.

SAMUEL BRADBURY.
